UNITED STATES PATENT OFFICE.

HAREY C. ATKINS, OF GREAT FALLS, MONTANA, ASSIGNOR OF ONE-HALF TO E. J. OWENS, OF GREAT FALLS, MONTANA.

CUE TIP.

Application filed July 5, 1921. Serial No. 432,573.

To all whom it may concern:

Be it known that I, HARRY C. ATKINS, a citizen of the United States, residing at Great Falls, in the county of Cascade and State of Montana, have invented new and useful Improvements in Cue Tips, of which the following is a specification.

My present invention has reference to an improved billiard cue tip.

10 My object is to produce, in a device of this character, means whereby an air cushion is provided between the tip and the end of a cue.

15 A further object is to produce a means for attaching a tip to a cue which will obviate the necessity of the employment of glue and the use of clamps in holding the tip on the cue during the drying process of the glue.

It is a still further object to produce a cue 20 that has its end provided with a reduced conical extension on which is arranged a metal conical sleeve which has its bore grooved longitudinally to receive therein the parts of the cue forced outwardly from 25 the conical extension when the sleeve is wedged thereon to afford a tight connection between the sleeve and cue, while on the sleeve there is threaded a ferrule which has secured in its outer end, in a novel manner, 30 the tip, the said tip having its inner portion in contacting engagement with the outer end of the sleeve and the latter projecting beyond the conical extension of the cue, whereby an air cushion chamber is provided 35 between the tip and cue.

The foregoing, and other objects which will appear as the nature of the invention is better understood, may be accomplished by a construction, combination and operative 40 association of parts, such as is disclosed by the drawings which accompany and which form part of this specification.

In the drawings:—

Figure 1 is a side elevation of a cue in accordance with this invention.

Figure 2 is a similar view with parts in section.

Figure 3 is a substantially central longitudinal sectional perspective view of the 50 sleeve.

Figure 4 is a central longitudinal sectional view through the ferrule showing the tip therein.

Referring now to the drawings in detail, 55 the cue is indicated by the numeral 1 and is

of the ordinary wooden construction. The cue, in the present instance, however, has its reduced end provided with a reduced conical extension 2. On the extension 2 there is received the conical sleeve 3. The sleeve is of a greater length than that of the extension 2, and therefore projects beyond the end of the extension. The sleeve 3 has its bore provided with longitudinal grooves 4 that are designed to receive therein the bunched or expanded parts of the wood fiber which are projected from the end 2 when the sleeve 3 is wedged on the said end 2. The sleeve at its inner and widened end is thickened on its outer surface, and the said thickened portion is provided with threads 6. Designed to be arranged over the sleeve 3 is a ferrule 7. The ferrule is also of a hollow frusto-conical formation and is of a greater length than the sleeve. The ferrule has its bore, at its inner and widened end provided with threads 8 that engage with the threads 6 of the sleeve 3. The bore of the ferrule is of a size to snugly engage the outer surface of the sleeve so that a tight joint is maintained between these elements.

The ferrule 7, at a slight distance from its outer and reduced end is provided with an annular inwardly rounded groove 9 and an annular cross sectionally angular lip 10 between the said outer end of the said groove.

The compressible tip is indicated by the numeral 11 and has its inner end reduced, as at 12. The outer edge of the reduced portion 12 is formed with an extension 13 that is rounded in cross section and which communicates with an inwardly directed angular groove 14. The groove 14 is designed to receive the lip 10 of the ferrule 7, and the rounded or ribbed portion 13 of the tip is designed to be received in the groove 9 of the ferrule 7. By reference to Figure 2 of the drawings, it will be seen that an air pocket 15 is provided between the inner end of the tip 11 and the outer end of the extension 2 of the cue. This pocket provides a dead air space and the air therein serves as a cushion for the tip.

It is thought that the foregoing description, when taken in connection with the drawings will fully set forth the construction and advantages of the improvement to those skilled in the art to which such inventions relate, and that further detailed description will not be required.

Having described the invention, I claim:—

A cue having a reduced frusto-conical extension at one end thereof, a frusto-conical metal sleeve of a greater length than the cue extension having its bore grooved and designed to be wedged on the cue extension, said sleeve having its inner widened end thickened on its outer surface and provided with threads, a frusto-conical ferrule of a greater length than the sleeve designed to be received over the sleeve and having its inner widened end interiorly reduced and threaded to engage with the threads of the sleeve,

said ferrule having its bore adjacent to its outer end provided with a continuous groove and an angular bead outward of the groove, a tip on the said end of the ferrule having a reduced portion provided with an outer bead and an inner groove to engage in the bead and groove of the ferrule, the said tip, when the ferrule is screwed on the sleeve, designed to contact with the outer end of the sleeve and to be spaced from the end of the cue to provide an air pocket therebetween. 25

In testimony whereof I affix my signature.

HARRY C. ATKINS.
